THREAD FEEDING DEVICE FOR THREAD
TESTING MACHINES

Walter Gegenschatz, Uster, Switzerland, assignor
to Zellweger A. G. Apparate-und Maschinen-
fabriken Uster, Uster, Switzerland, a corpora-
tion of Switzerland

Application April 4, 1951, Serial No. 219,191
In Switzerland April 14, 1950

7 Claims. (CL. 73—160)

1

The present invention refers to thread testing machines of the type in which successive lengths of thread are subjected to tensile stress and more particularly to novel and improved means for successively feeding lengths of thread into such testing machines.

It is an object of the invention to provide thread supply means for automatically successively delivering lengths of thread from a source of thread supply to a tensioning and tension measuring mechanism including two clamps between which a length of thread is held for the testing operation. The supply means according to the invention comprise a gripper connected with an endless chain travelling around a loop, the gripper being adapted to grip the thread extending from a source of thread supply, laying the thread into said clamps, and releasing the thread after it has been taken over by the clamps. The use of an endless chain for guiding the gripper along a predetermined path, makes it possible to shape said path to suit the requirements of a variety of clamp arrangements of conventional thread testing devices by suitably placing sprocket wheels supporting the chain. The thread gripper carried along by the chain may itself be used as one of the clamps holding the ends of the lengths of thread to be tested and the pull of the chain may be utilized for providing the force for tensioning and breaking the thread to be tested, the tension force applied to the thread during the test being measured by conventional means which are connected with the clamp holding one end of the length of thread to be tested.

Further and other objects of the present invention will be hereinafter set forth in the accompanying specification and claims, and shown in the drawings which, by way of illustration, show what I now consider to be preferred em- 40 bodiments of my invention.

In the drawings:

Fig. 1 is a part sectional side elevation of a machine according to the invention;

Fig. 2 is a part sectional front elevation of the machine shown in Fig. 1 with parts of the casing broken off;

Fig. 3 is an electric wiring diagram of a machine according to the invention;

Fig. 4 is a diagrammatic front view of a mechanism according to the invention;

Fig. 5 is a large scale view from below of a thread gripper according to the invention;

Fig. 6 is a longitudinal sectional view of the thread gripper shown in Fig. 5;

2

Fig. 7 is a rear view of the gripper shown in Figs. 5 and 6 with part of the chain to which it is attached, the gripper proper being shown in a section transverse to its longitudinal axis;

Fig. 8 is a diagrammatic front view of a modified mechanism according to the invention;

Fig. 9 is a diagrammatic front view of a further modification of a mechanism according to the invention.

Referring now particularly to Figs. 1 and 2 of the drawings, numerals 2 and 3 designate thread clamps for holding a length of thread which is to be tested. The lower clamp 3 is stationary. The upper clamp 2 is provided with a bracket 2' which is suspended on ribbons 5 extending over a roller 4 rotatably supported on casing 7. The ribbons 5 are connected with a carriage 6 rolling on a support 8 one end of which is swingably connected with the casing 7, coaxially with roller 4. The other end of support 8 is provided with a roller 10 resting on a platform or table 9.

The pull exerted through ribbons 5 on the thread 1 clamped in clamp 2 depends on the weight of the carriage 6 and on the inclination of the support 8. The inclination can be adjusted by changing the elevation of platform 9. This is done by rotating a vertical threaded roll 11 extending through a nutlike portion 11' of table 9. Rotation of the latter is prevented by a vertical rod 12 which guides the table slidably. The weight of the clamp 2 and bracket 2' is counterbalanced by a weight 75 suspended on roller 4.

The testing machine is driven by a motor 13 permanently rotating pulley 15, which is fast on machine drive shaft 16, by means of a belt 14. The rotation of shaft 16 is transmitted by spur gears 23, 26, 25 and part 20 of a magnetic clutch which part rotates freely on shaft 17. The other part 20 of the clutch is axially slidably keyed to shaft 17. The rotation of shaft 16 is also transmitted, in reverse, by means of spur gears 22, 24 to a magnetic clutch part 19' which rotates freely on shaft 17, the other part 19 of the clutch being axially slidable but not rotatable on shaft 17. Gear wheel 22 is in mesh with a gear wheel 27 fast on clutch part 21' which is rotatable on a shaft 18 and cooperates with a magnetic clutch part 21 axially slidable but not rotatable on shaft 18.

Shaft 17 rotates threaded rod 11 through bevel gears 28 in opposite directions depending whether clutch 19 or 20 is energized.

Shaft 18 rotates a shaft 30 through worm gears 55, 29, 31. Shaft 30 carries cams 32, 33 and 51. Cam

32 is in contact with a follower roller 34 on one end of lever 35 swinging about a pin 36. The other end of lever 35 has an elongated slot 37 through which extends a pin 38 on rod 39. The latter is pivoted to one arm of the elbow levers 40 and 41, the other arms of the levers 40 and 41 being adapted to abut against the ends of stems 2" and 3', respectively, of the thread clamps 2 and 3 for opening same against the action of springs.

Cam 33 engages follower roller 42 on lever 44 which swings on a stationary pin 43. The free end of lever 44 is linked to an arm member 46 by a connecting rod 45. Member 46 is fast on two rods 47 vertically guided in guides 48 and pressed upwards by a spring 49. The upper ends of rods 47 extend through large holes 50 in the bracket 2' and are provided with heads 77 outside of the bracket for upward travel of the rods through holes 58 prior to upward movement of clamp 2 during a thread tensile strength test and effecting return of clamp 2 to its initial position shown in Figs. 1 and 2 after completion of the test, upon downward movement of the rods 47. When the clamp 2 is in its initial position, its stem is in a position in which it can be engaged by lever 40 for opening the clamp.

For a better understanding of the operation of the thread testing device, reference is made to the electric wiring diagram, Fig. 3. A switch 63, 64 is closed simultaneously with a switch or other device 13' for starting the motor 13. Closing of switch 63, 64 energizes lines 63' and 64' feeding the magnetic clutches 19, 20 and 21.

Clutch 20, which effects upward movement of table 9, is energized upon closing of switch 58 and of switch 53, 54. As seen in Fig. 1, switch 58 is closed whenever table 9 is not in uppermost position; table 9 is provided with an extension whose top and bottom are insulated by insulators 56 which contact arms of switches 57 or 58 for opening same depending whether the table is in lowest or uppermost position. The movable central member 53 of two-way switch 53, 54 and 53, 55 as actuated by a plunger 52 which is responsive to the position of cam 51.

Energization of clutch 19 causes downward movement of table 9 which is needed for making a thread test. Clutch 19 receives current upon closing of contacts 53 and 55, which is effected by cam 51, and of switches 57 and 59. Switch 57 is closed whenever table 9 is not in its lowermost position. Switch 59 is closed as long as arm 69' of a thread feeler 60 is held in the position shown in Fig. 1 by the lower end of one of the rods 47. The first step for making a thread test is the release of rod 45 by cam 33 to produce quick upward movement of rods 47 by the action of springs 49 and release of the bracket 2'. This being done, the feeler 60 rests on the tensioned thread 1 which prevents spring 61 from pulling arm 69' against the switch 59 for opening it. To prevent the thread 1 from yielding to the pressure of feeler 60, a pin 62 is provided on the side of the thread opposed to that where the feeler is located. When the thread breaks, feeler 60 and its arm 69' turn counterclockwise due to the action of spring 61 and the arm 69' opens contact 59 thereby de-energizing clutch 19 and interrupting downward movement of table 9, whose position indicates the force which was required to break the thread.

Energization of clutch 19 is accompanied by energization of solenoid 65 and opening of contacts 66 whereby clutch 21 is de-energized and

shafts 18 and 30 are stopped as long as table 9 moves downward, i. e., during a thread test.

In the foregoing, mechanisms are described which are of a kind used in conventional thread testing machines. The following relates to means according to the invention for continuously feeding new lengths of thread to extend between the clamps 2 and 3 to be held thereby for testing. These means comprise a chain 68 which forms a loop extending around four sprocket wheels 69, 70, 75 and 76, wheels 69 and 70 being visible in Figs. 1 and 2, wheels 75 and 76 being shown diagrammatically in Fig. 4. Wheel 69 is connected to shaft 18 by means of a speed reducing gear 17 and driven thereby.

One link of chain 68 is provided with a thread gripper 67 which is illustrated in a larger scale in Figs. 5, 6 and 7. Clamp part 78 has a stem 79 which is screwed into sleeve 80. The latter is slidable in a cylinder 81 having a head 82 forming the counterpart to clamp part 78. Spring 83' presses part 78 against the head 82. Sleeve 80 has a slot 83 extending transversely to its longitudinal axis and receiving the head 84 of a pin 85 which is rotatable in a holder portion 86 to which the cylinder 81 is secured and which is connected with a link of the chain 68. The head 84 has a flat surface 87 which is parallel to an interior surface of the slot 83 when the clamp is closed, i. e. in the position shown in Figs. 5 to 7. If pin 85 is rotated 90° the head 84 pushes sleeve 80 against the action of spring 83' and opens the thread gripper 78, 82. To effect rotation of the pin 85, its outer end is provided with a wing part having two wings 73, 74 adapted to be engaged by stationary catches 71, 72, respectively (Figs. 1 and 2), when the gripper moves past said catches in the direction indicated by arrow 88 in Fig. 5. Catch 72 which is in the position A in the diagram Fig. 4 opens the gripper 67 and catch 71 closes it when the gripper reaches the position indicated by letter B in Fig. 4. The chain 68 and its mechanism are so designed that during one revolution of the control shaft 30 gripper 67 travels once around the loop formed by chain 68. Since clutch 21 is disengaged during the time a thread length is tested, shafts 18 and 30 and consequently chain 68 and gripper 67 do not move during the test period.

For setting up the machine, thread is pulled from bobbin 89, laid into guide 90 and clamped into gripper 67, if the latter is in the neighborhood of sprocket wheel 75; if not, the thread is laid into clamps 2 and 3. By starting the motor 13, clutch 21 is energized and shaft 18, which drives the chain 68 and the control shaft 30, is rotated, cam 33 permits rods 47 to move upward for releasing the clamp holder 2' and permitting the clamp 2 to be pulled upward by the testing mechanism 4, 5, 6, 8, 9. As soon as contacts 53, 55 are closed clutch 19 and solenoid 65 are energized whereby clutch 21 is de-energized and shaft 18 is stopped and shaft 17 rotated to move table 9 downward for making a thread breakage test. The moment the thread breaks, thread feeler 60, 60' opens switch 59 whereby clutch 19 and solenoid 65 are de-energized and clutch 21 is energized and chain 68 is moved in the direction of arrow 88 with the thread gripper 67 open. Cam 33 returns, through members 44 to 47, clamp 2 and the thread tensioning and testing mechanism to initial position, in which rods 47 are in lowermost position and the lower end of one of them holds thread feeler 60 in position to receive a thread 75 and switch 59 closed for the next testing period.

When the open gripper 67 reaches position B, it contacts the thread extending between guide 90 and clamp 2 and subsequently grips it when the gripper is closed due to engagement of wing 73 with catch 71. The chain and gripper attached thereto continue to travel thereby laying the thread consecutively into clamps 2 and 3 which are held open by the action of cam 32 and the mechanism 34 to 41. When the thread gripper approaches position A in Fig. 4, clamps 2 and 3 are closed and the gripper is opened because wing 74 is engaged by catch 72. The machine is now ready for testing the length of thread between the clamps 2 and 3 and the chain is stopped and the test begins as soon as cam 51 closes contacts 53, 55. Prior to this, contacts 53 and 54 were closed and shaft 17 rotated simultaneously with shaft 18 for returning table 9 to its top position in which it opened switch 58 for stopping shaft 17.

Fig. 8 diagrammatically illustrates a modification of the machine according to the invention in which the stationary thread clamp 3 is omitted and replaced by the thread gripper 67. Since the chain 68 and the gripper are at a standstill during actuation of the thread testing mechanism, gripper 67 can be used as stationary thread clamp for testing the thread.

Fig. 9 illustrates diagrammatically a further modification of the machine according to the invention. In this case, as in the one shown in Fig. 8, the thread gripper 67 serves for holding one end of the thread length to be tested during the test. It is, however, not stationary but moves from position C to D for stretching the thread. The force exerted on the thread up to the time it breaks is measured by conventional tension force reaction and measuring means 91 which are not shown in detail as they do not form part of the present invention. After gripper 67 has reached position D, it is opened by a catch 72 in the same manner as in Figs. 4 and 8. The open gripper travels with the chain and receives thread coming from spool 89 upon reaching position E. Thereafter, the gripper is closed by engagement with catch 71, as described previously. Instead of one sprocket wheel 75, as in Figs. 4 and 8, two wheels 75' and 75'' are provided for guidance of the chain so that the gripper holding a fresh supply of thread to be tested has travelled past the clamp 2 by a distance corresponding substantially to the length of thread to be tested before the thread is laid into the clamp.

While I believe the above described embodiments of my invention to be preferred embodiments, I wish it to be understood that I do not desire to be limited to the exact details of method, design, and construction shown and described, for obvious modifications will occur to a person skilled in the art.

I claim:

1. A thread testing machine having thread tension measuring means including a thread clamp supporting a length of thread to be tested, a source of thread from which thread to be tested extends to said clamp, a chain forming a loop, sprocket wheels supporting said chain in a plane substantially parallel to the length of thread to be tested, drive means connected with at least one of said sprocket wheels for moving said chain, and a thread gripper connected with said chain and extending laterally thereof and being moved thereby in a path looped around said clamp, said gripper being adapted to grip the thread extend-

ing from said source and to lay the thread into said clamp.

5. A thread testing machine comprising a source of thread, thread tension measuring means including a thread clamp for supporting a length of thread to be tested, thread supply means including a chain, sprocket wheels supporting said chain to form a loop, drive means connected with at least one of said wheels for moving said chain, and a thread gripper connected with said chain to move therewith and adapted to grip the thread extending from said source and to lay it into said clamp while the gripper moves with the chain around a loop-shaped path extending around said clamp.

3. A thread testing machine comprising a source of thread to be tested, thread tension measuring means including a thread clamp for supporting a length of thread to be tested, thread supply means including a chain, rotatable means supporting said chain to form a loop situated in a plane parallel to the length of thread to be tested, drive means connected with said rotatable means for moving the chain around the loop formed thereby, and a thread gripper connected with and extending laterally of said chain and travelling in a loop extending around said clamp and being adapted to grip the thread extending from said source and to lay it into said clamp.

4. A thread testing machine comprising a source of thread to be tested, thread tension measuring means including a thread clamp for supporting a length of thread to be tested, thread supply means including a chain, rotatable means supporting said chain to form a loop situated in a plane parallel to the length of therad to be tested, drive means connected with said rotatable means for moving the chain around the loop formed thereby, a thread gripper connected with and extending laterally of said chain and travelling in a loop extending around said clamp and being adapted to receive the thread extending from said source and to lay it into said clamp, and stationary means disposed in the path of said gripper and adapted to close it after it has received a thread and to open it after it has laid the thread into said clamp.

5. A thread testing machine comprising a source of thread to be tested, thread tension measuring means including two thread clamps for supporting a length of thread to be tested therebetween, thread supply means including a chain, rotatable means supporting said chain to form a loop situated in a plane parallel to the length of thread to be tested, drive means connected with said rotatable means for moving the chain around the loop formed thereby, and a thread gripper connected with and extending laterally of said chain and travelling in a loop extending around said clamps and being adapted to grip the thread extending from said source and to lay it into said clamps.

6. A thread testing machine comprising a source of thread to be tested, thread tensioning means including a thread clamp clamping one end of a length of thread to be tested, a chain, rotatable means supporting said chain to form a loop situated in a plane parallel to the length of thread to be tested, drive means connected with said rotatable means for moving the chain around the loop formed thereby, a thread gripper connected with and extending laterally of said chain and travelling in a loop extending around said clamp and adapted to grip the thread ex-

tending from said source and to lay the thread into said clamp, and means interposed between said drive means and said rotatable means for interrupting movement of said chain and said gripper after the latter has travelled past said clamp by a distance corresponding to the length of thread to be tested.

7. A thread testing machine comprising a source of thread to be tested, thread tension force reacting and measuring means including a thread clamp clamping one end of a length of thread to be tested, a travelling chain forming a loop situated in a plane parallel to the length of the thread to be tested, a thread gripper connected with and extending laterally of said chain and adapted to grip the thread extending from said source, rotatable means supporting said chain and being so located as to guide the chain on a path of such configuration around said clamp that the thread is laid into the clamp 20

after said gripper has travelled past said clamp by a distance corresponding substantially to the length of the thread to be tested, and drive means connected with said rotatable means for causing said chain and gripper to travel around said loop and exerting pull through said gripper on said thread against the action of said tension force reacting and measuring means after the thread has been laid into said clamp.
